UNITED STATES PATENT OFFICE.

HERBERT R. NEVENS, OF PORTLAND, MAINE.

ATTACHMENT FOR LOCOMOTIVE AIR-BRAKES.

SPECIFICATION forming part of Letters Patent No. 739,907, dated September 29, 1903.

Application filed February 10, 1902. Serial No. 93,287. (No model.)

To all whom it may concern:

Be it known that I, HERBERT R. NEVENS, a citizen of the United States of America, and a resident of Portland, Cumberland county, 5 State of Maine, have invented certain new and useful Improvements in Attachments for Locomotive Air-Brakes, of which the following is a specification.

My invention relates to an attachment to 10 the air-brakes of railroad-trains whereby the same may be set by a brakeman on the track in front of the train.

It sometimes happens that when a brakeman is sent back on the track to flag an on- 15 coming train his signals are not seen on account of fog or darkness or the carelessness of the engineer and a rear-end collision results. The object of the present device is to prevent such collisions by so constructing the 20 air-brake apparatus that the brakeman may automatically apply the brakes if his signals are not seen. I accomplish this object by providing a valve for releasing the pressure on the train line-pipe, with a depending arm 25 for operating said valve in front of the front truck of the locomotive and with its lower end adjacent to the top of the rail, in connection with a tripping-plate adapted to be carried by the brakeman and fastened on top of 30 the rail, so that as the arm comes in contact with the tripping-plate the valve is opened and the brakes set.

I illustrate my invention by means of the accompanying drawings, in which—

35 Figure 1 is a side elevation of my attachment, showing the forward truck, partly in section. Fig. 2 is an enlarged side elevation with the valve in section. Fig. 3 is a front elevation. Fig. 4 is a plan view of the tripping device, and Fig. 5 is a modification of the arm.

A represents the wheel of the forward truck. a is the axle, and c is the frame. Secured to the frame is the piston-valve B, connecting 45 by a pipe n with the train line-pipe m. A cam is provided by which the piston-valve may be opened to relieve the pressure on the train line-pipe. As here shown, a cam f is secured to a transverse shaft e and acts against the 50 valve-stem i of the piston-valve. In the end of the piston are two ports p and p', the port p communicating with the open air and the

port p' with the whistle o, which is preferably located in the cab of the engine. Secured to the valve-stem and against the end of the 55 cylinder is the piston i', having an opening i³ through it out of line with the ports, so that when the piston is shut the ports are closed. A guide i² is located back of the piston to guide the valve-stem. 60

The working edge of the cam f has a concave portion f², against which the end of the valve-stem rests normally, so that when the cam is turned in either direction the valve-stem is pressed inward and the valve opened. 65 On each side of the concave portion f² there is a convex portion f¹, here shown as concentric with the center of the cam and far enough away to hold the valve open when the stem reaches this part of the cam. Thus when the 70 cam is turned in either direction the valve is first forced open by the surface f² and held open by the surface f¹. The cam is turned to open the valve by means of a depending arm d, one of which hangs down from each 75 end of the shaft directly over the rail and in front of the wheel A. The shaft e is journaled in the boxes q, secured to the frame by the braces g.

The lower end of the arm d is adjacent to 80 the track and easily thrown back by any obstruction on the track. For the purpose of swinging the arm to open the valve the brakeman is provided with a tripping-plate adapted to be attached to the track. As here shown, 85 I show an elongated plate j, having clips j, by which it is fastened to the track, and having a crowning portion j', which rises above the surface of the rail and against which the lower end of the arm is adapted to hit. For 90 the purpose of extra precaution a torpedo k may be secured to the tripping-plate.

The operation of the device is as follows: When the brakeman desires to stop the on- 95 coming train, he flags the train in the usual manner, and if he gets the signal from the engineer that his flag is seen he does not make use of the tripping-plate; but if he does not get the signal he secures the tripping-plate to the rail, and when the locomotive 100 comes along the front wheels run into the end of the tripping-plate and hold it firmly down, while the arm d comes along and striking against the crowning portion j' turns the

shaft and the cam and opens the valve, causing the pressure on the train line-pipe to be relieved, and so setting the brakes.

It will be seen that the tripping device will 5 seldom have to be used; but it is taken along by the brakeman when he starts back with his flag or lantern as an extra precaution to be used if his signals are not seen.

In Fig. 5 I show a modified form of arm 10 having a wheel *s*, which tends to lift as it strikes the tripping-plate instead of being thrown back, as does the arm of Fig. 1.

I claim—

1. In a device for automatically setting air-brakes on a railroad-train, the combination 15 of a piston-valve for relieving the pressure on the train line-pipe, a valve-stem for said valve, a cam acting against said valve-stem to open the valve against the pressure, a shaft 20 for said cam, a depending arm on said shaft and a tripping device on the track adapted to strike said arm.

2. In a device for automatically setting air-brakes on a railroad-train, the combination

of a piston-valve secured to the truck for relieving pressure on the train-pipe, a cam acting against the valve-stem of said valve, a transverse shaft for said cam journaled in said truck, an arm depending from each end of said shaft having its lower end adjacent to the top of the rail.

3. In a device for automatically setting air-brakes on railroad-trains, the combination of 35 a piston-valve secured to the truck for relieving pressure on the train-pipe, a cam acting against the valve-stem of said valve, said cam having a portion concave with respect to said valve-stem for opening the valve and a convex portion for holding the valve open, a transverse shaft for said cam, an arm depending from each end of said shaft having its lower end adjacent to the top of the rail.

Signed at Portland, Maine, this 3d day of February, 1902.

HERBERT R. NEVENS.
